UNITED STATES PATENT OFFICE.

FRANK VAN INWAGEN, OF CHICAGO, ILLINOIS, ASSIGNOR OF ~~THE~~ ONE-FOURTHS TO
GORDON L. HARRIS, OF CHICAGO, ILLINOIS.

FLUID-REMOVING DEVICE.

Application filed April 18, 1921. Serial No. 462,469.

To all whom it may concern:

Be it known that I, FRANK VAN INWAGEN, a citizen of the United States, residing in the city of Chicago, county of Cook, and State of Illinois, have invented certain new and useful Improvements in Fluid-Removing Devices, of which the following is a specification.

This invention relates to improvements 10 in fluid scavenging devices and refers more particularly to devices, designed to assist in the removal of fluids, both liquids and gases from heating systems, dryers, evaporators, or other steam or liquid 15 circulatory heating, drying or evaporating systems and is applicable to so-called vacuum heating systems.

The salient object of the invention is to 20 provide a device which will economically withdraw from such a system the condensation liquid and such air or fluid as may be contained therein and to deliver such condensate separately to a boiler or other reservoir and also to separately deliver any 25 entrained air or light non-liquid gases or vapors through a separate system of piping to the atmosphere or other container as desired.

The single figure of the drawing is an ele- 30 vational view of the apparatus with parts broken away.

Considerable difficulty has been encountered by devices being manufactured to accomplish the removal of the gases and liquid 35 from systems of the type described but not an economical device has been produced as yet which will properly eliminate such fluids. I have combined into one unit certain well known devices which have the 40 ability to do one or more of the aforementioned processes and assembled into a single packing machine, the necessary apparatus to effect all of these operations with the minimum expenditure of power. In

45 the past it has been difficult to arrange for the removal of the liquid separately from the lighter vaporous fluids when there is a steady action or vacuum pull on the returns from the system. I have, therefore, 50 arranged an interrupting device which intermittently and automatically interrupts the suction of the lighter fluids or the vacuum produced so that the heavier liquids

may be more easily drawn off to a liquid handling pump. In general, I have de- 55 signed an improved, compact, easily operated and semi-automatic device.

Referring in particular to the drawings, the general arrangement of the mechanism as shown in the drawing is connected to the 60 drain line from the heating system, condensers, evaporators or other device. The returns from these systems enter through the line 1 and pass through the check valve 2 into receiver 3. This receiver is of a size 65 sufficient to permit the separation by gravity of the gaseous fluid which mingles with the vapor and fills the upper part of the receiver. The lower part of the receiver holds the heavier liquid which has a tendency to drain off through the pipe 4 into the suction side 5 of the pump 6. This pump as shown is of the centrifugal type being driven through the horizontal shaft 6^a by 70 motor 6^b. This motor operating the centrifugal pump forces the liquid through the delivery line 7 to the line 8 in which is interposed a check valve 9. The liquid from the line 8 is directed to any convenient receptacle for such water or liquid, whether 75 it be a boiler, receiver, tank or to the sewer as desired. The check valve is interposed to prevent any back flow to the pump when 80 it is shut down or when there exists less pressure within the pump than exists in the 85 boiler, receiver, or other collecting reservoir. By means of this apparatus, water or other liquids may be rapidly removed from the receiver but as centrifugal pumps are notoriously inefficient in circulating liquids or 90 fluids which possess a low specific gravity, the air, vapor or lighter fluids must be withdrawn from the receiver 3 through a separate device which shall have the quality of 95 being a positive vacuum producing mechanism.

The lighter or gaseous fluids are removed from the top of the receiver through a line 10, connecting leads 11, which convey the lighter fluids to the suction connection of a 100 positive type of vacuum producing mechanism designated as 12. This mechanism is preferably of rotary type so that it may be directly connected to the shaft 6^a which operates the centrifugal pump 6. When the 105 mechanism is in operation it will be seen

that a positive displacement of the lighter fluids and air in the upper part of the receiver 3 will be accomplished and these lighter fluids will be removed. These 5 lighter fluids discharged from the vacuum pump 12 are discharged through the pipe 13, in which is interposed a check valve 14, either to the atmosphere or to suitable collecting receptacle.

10 Experience has proven, however, that this operation of a positive fluid handling device such as a pump 12 will cause a relatively high vacuum to exist on the receiver 3, thus seriously interfering with the easy drainage 15 of the heavier liquids contained in the receiver and checking, to a certain extent, the amount of liquid which will drain through the pipe 4 and be handled through the centrifugal pump 6. This high vacuum tends to 20 maintain a liquid level in the tank 3 and to take advantage of this level to cause a more desirable operation, I have designed an interrupting device, consisting principally of a float mechanism pivoted within the tank 25 and indicated at 14. To the arm of this float is attached a valve 15 which seats in the opening in the top of the receiver which leads to the line 10. The float arm is pivoted at 16 on a bracket 17 within the receiver 30 and as the float arm rises with the liquid level of the receiver, the outlet line will be closed by means of the valve 15. The closing of this valve throttles the vacuum imposed upon the liquid in the tank, obviating 35 its effect and permitting the liquid to drain freely through the line 4 to the centrifugal pump 6. As the liquid level lowers with the draining of the receiver, the valve 15 will again open and the lighter fluids again pass 40 off through the outlet line 10 to the vacuum pump 12 as explained. This action will prove more or less intermittent but will

overcome difficulties heretofore experienced in handling properly the returns from systems of the type mentioned.

45

I claim as my invention:

1. In a fluid removing device for the removal of fluids from systems, the combination with a collecting means connected with the system outflow line, of liquid and gas drawoffs connected thereto, means automatically controlled by the liquid level in the collecting means for controlling the withdrawal of the gas and liquids removed from the system.

55

2. In a fluid removing device for the removal of fluids from systems, the combination with collecting means connected with the system, of liquid and gas drawoff lines connected thereto, separate means for removing the gas and liquid from the collecting means, and automatic means operable to control the vacuum imposed upon the collecting means and the withdrawal of liquid and gaseous fluids from the system.

65

3. In a fluid removing device for the removal of fluids from systems, the combination with a means connected to an outlet of the system for collecting the fluids drained therefrom, of liquid and gaseous fluid draw-off lines connected thereto, a float and valve for the gas outlet actuated by the liquid level to vary the vacuum imposed upon the system and to regulate the relative flows of gas and liquid from the collecting means.

75

4. In a fluid removing device for the removal of fluids from systems, the combination with a collecting means connected with the system outflow line, of liquid and gas drawoffs connected thereto, and automatic means for varying the vacuum imposed upon the collecting means and for controlling the relative gaseous and liquid drains.

FRANK VAN INWAGEN.
